J. Gregg,

Brick Machine.

N° 8,284.

Patented Aug. 5, 1851.

UNITED STATES PATENT OFFICE.

ISAAC GREGG, OF PITTSBURGH, PENNSYLVANIA.

BRICK-MACHINE.

Specification of Letters Patent No. 8,284, dated August 5, 1851.

To all whom it may concern:

Be it known that I, ISAAC GREGG, of Pittsburgh, in the county of Allegheny and State of Pennsylvania, have invented sun-
5 dry new and useful Improvements in Ma-
chines for Making Bricks of Untempered Clay; and I do hereby declare that the fol-
lowing is a full and exact description there-
of, reference being had to the accompanying
10 drawing, making a part of this specification.

In its general construction and operation, the brick machine containing the within de-
scribed improvements, is similar to that pat-
ented by me June 16th, 1848; the clay being
15 thrown into a hopper A, containing a heavy
pressure roller B, by which the clay is
forced through an opening in the bottom of
the hopper into a series of molds that are
made to pass back and forth under the same
20 by means of a pitman or other equivalent
contrivance.

In the machine patented by me June 16th,
1848, before referred to, the molds were
25 made of extra depth, and the clay forced
into them to form the bricks, was by a pre-
liminary process, elevated therein a distance
equal to the extra depth of the molds; and
the surplus clay thus elevated above the tops
30 of the molds was cut off by a knife which
left the upper surfaces of the molded
bricks hard and smooth, and their angles
perfect; when the said molded bricks were
removed from the molds in the usual man-
ner.

35 In this my improved machine, I also make
the molds of extra depth, and after forcing
the clay into them by the large roller B, I
partially elevate the compressed clay therein
for the purpose of subjecting the same to
40 further action by which a more perfect form
is given to the molded bricks. Before I
subject the surplus clay elevated above the
tops of the molds to the action of the knife
n, I act upon it a second time by pressure,
45 by means of a small roller or stationary bar
p, placed a short distance in front of the
said knife, which is more minute in its op-
eration than the large roller B, and serves to
force the clay more perfectly into the angles
50 of the molds; and the interposition of this
second pressure roller, or bar, between the
main pressure roller and the knife n, con-
stitutes my first improvement in the afore-
said machine for making bricks of untem-
55 pered clay.

My second improvement consists in plac-

ing a transverse plate m, in the rear of the
knife n—the under surface of which is made
perfectly even and smooth,—and in connec-
tion therewith, slightly elevating the false
bottoms e, e, of the molds when they are
60 passing under the said plate, for the pur-
pose of subjecting the clay in the molds to
additional compression against the same,
and in consequence of this action causing
65 so great an amount of friction to be exerted
upon the upper surface of the clay in each
of the molds, as to move the body thereof
toward the rear and press it against the rear
side of the mold with sufficient force to give
70 to the after edge and angles of each molded
brick, as smooth and perfect a form as can
be shaped by any other process; and making
a solider and more uniformly compacted
brick than has ever been formed by any
75 other process.

The false bottoms e, e, of the molds may
be elevated by any mechanical contrivance
that may be deemed expedient.

The accompanying drawing is a longitu-
dinal vertical section of a brick machine
having these my latest improvements.

f, f, are legs descending from the movable
bottoms e, e, of the molds; and g, g, are
friction rollers combined with the lower
85 ends of the said legs.

j, is a roller for giving the first partial
elevation to the bottoms of the molds, and
k, is a plane surface extending forward
from the roller j for the legs of the bottoms
90 of the molds to rest and traverse upon while
the pressure roller, or bar p, is acting upon
the clay in the molds, and the knife n, is re-
moving the surplus portions thereof.

l, is a roller at the front end of the plane
95 k, for giving the second partial elevations
the bottoms of the molds while they are
passing beneath the plate m. After this
last operation, the mold bricks are raised
100 out of the molds by means of an inclined
plane t, for the legs descending from the
bottoms of the molds to pass over, or by
any other suitable contrivance.

The roller k, upon the arbor i, bears
against the under side of the carriage con-
105 taining the molds, immediately under the
large pressure roller B.

What I claim as my invention and de-
sire to secure by Letters Patent, is—

1. The placing the auxiliary pressure roller
110 p,—or its equivalent—between the main
roller B, and the knife n, for the purpose of

subjecting the surplus clay, after it is elevated above the tops of the molds, to the action of pressure before removing the same by the said knife, substantially as herein set forth.

2. I also claim the subjecting the upper surface of the clay in each mold to a rubbing pressure, by means of a plate *m*—or its equivalent—placed above the tops of the 10 molds, in combination with some mechanical device for forcing up the movable bottoms

of the said molds while passing under the said plate, substantially in the manner and for the purpose herein set forth.

The above specification of my improvements in brick-machines signed this 14th day of July, 1851.

ISAAC GREGG.
